Patented Apr. 20, 1909.

2 SHEETS—SHEET 2.

UNITED STATES PATENT OFFICE.

BERNARD ARTHUR BEHREND, OF NORWOOD, OHIO, ASSIGNOR, BY DIRECT AND MESNE ASSIGNMENTS, TO THE BULLOCK ELECTRIC MANUFACTURING CO., A CORPORATION OF OHIO, AND ALLIS-CHALMERS COMPANY, A CORPORATION OF NEW JERSEY.

FIELD-MAGNET.

No. 918,499.

Specification of Letters Patent.

Patented April 20, 1909.

Application filed May 14, 1904, Serial No. 207,921. Renewed July 29, 1907. Serial No. 385,998.

To all whom it may concern:

Be it known that I, BERNARD ARTHUR BEHREND, a citizen of the United States, residing at Norwood, in the county of Hamilton and State of Ohio, have invented certain new and useful Improvements in Field-Magnets, of which the following is a full, clear, and exact specification.

My invention relates to dynamo electric machinery and particularly to revolving field magnets.

The object of my invention is to provide a field magnet construction adapted for very high speeds such as is necessary in generators directly connected to steam turbines. At such high speeds the usual constructions are not adapted to withstand the enormous centrifugal strains developed and special construction of certain parts is necessary.

The subject matter of the present application relates particularly to means for supporting and protecting the windings, certain other improvements being herein shown and described but which are claimed in my co-pending application filed April 9, 1904, Serial Number 202353.

In usual constructions the field coils are retained in position by the pole tips and flanges on the end plates and the larger component of the centrifugal force on the windings is directed against the said tips. In high speed machines however, the number of poles becomes very small and their size is increased which results in greatly increasing the component of the centrifugal force exerted on the winding in a direction at right angles to the sides of the pole. This component causes the coils to be thrown outwardly at the sides and my present invention relates to the overcoming of such displacement or tendency.

My invention will be understood from the following description and accompanying drawings and the novelty thereof will be more definitely set forth in the claims.

Figure 1 is a part longitudinal section and part side view of a revolving field magnet embodying my invention; Fig. 2 is an enlarged part cross section and part end view of the same.

The supporting element comprises a solid integral member and in the present instance is shown as carrying four poles. It is spe-

cially designed to have great mechanical strength and at the same time fulfil the magnetic requirements. The body portion 1 is square in section and is slotted to receive the dovetails 2 of the pole pieces. The body portion is provided with gradually tapering integral extensions 3 which reduce to the supporting journals 4. The whole is made of some material having great mechanical strength and high magnetic permeability such as forged nickel steel.

The pole pieces are built up of laminæ 5 secured to the supporting element by dovetails. The laminæ are clamped between the end plates 6 by means of the through bolts 7. The coil for each pole piece is subdivided into an inner part 8 and an outer part 8' and separated by a spacer 9 of suitable material which encircles the pole. The coil is located between the core and the extensions 10 of the pole. On the sides of the pole pieces and over the windings are placed plates 11 for retaining the windings in place and protecting the same. The plates are shown as notched into the core 1 at their inner edges, and engaged by the tips 12 of the pole pieces at their outer edges. The plates are retained in position by the bolts 13 which pass through the pole pieces and plates, the nuts 14 of the bolts being shown recessed into the side plates. The bolts 13 pass between the divided portions of the coils and through holes provided in the spacers 9 which may be solid except for the openings for the bolts 13 or may be of skeleton form, or if desired may consist simply of blocks placed between the bolts 13.

The end turns of the coils are shown as protected and supported by U shaped castings 15, the ends of the same being provided with dove tails 16 which engage the core 1. The windings pass from under the plates 11 and into the spaces between the arms of the castings 15 and thus all parts are firmly held in position. The spacing blocks 17 are placed between the dove tail projections of the U shaped members 15. The outer ends 100 of members 15 are held in place by the through bolts 18. The pole pieces are prevented from moving sidewise by the end plates 19, shown partly broken away in Fig. 2, and which are secured to the core by the bolts 20. The usual collector rings 21 are

provided, the leads 22 to the coils being placed diametrically opposite each other so as to be balanced.

Although I have shown and described a specific embodiment of my invention, I am not limited to the exact construction shown and the construction may be varied and still be within the scope of the claims.

Having thus described my invention, I declare that what I claim as new and desire to secure by Letters Patent, is—

1. In a dynamo electric machine, the combination with the revolving element and field magnets thereon, of side supports for the windings of said field magnets, and means passing into the pole pieces and between parts of the winding for each pole piece for retaining the said supports in position, substantially as described.

2. In a dynamo electric machine, the combination with the revolving element and field magnets thereon, of side supports for the windings of said field magnets, and bolts passing through the pole pieces for retaining the side supports in position, substantially as described.

3. In a dynamo electric machine, the combination with the revolving element and field magnets thereon, of side plates for the windings of said field magnets, and means passing through the pole pieces and windings for retaining said plates in position, substantially as described.

4. In a dynamo electric machine, the combination with the revolving element and pole pieces thereon, of a divided winding for each pole piece, side supports for the windings, and means passing through the pole pieces and between the parts of the divided windings for retaining said side supports in position, substantially as described.

5. In a dynamo electric machine, the combination with the revolving element and pole pieces thereon, of a divided winding for each pole piece, side supports for the windings extending between the core and tips of the pole pieces, and means passing through the pole pieces for retaining said side supports in position, substantially as described.

6. In a dynamo electric machine, the combination with the revolving element and pole pieces thereon, of a divided winding for each pole piece, said winding being seated between the core and extensions on the pole pieces, side supports for the windings extending between the core and pole tips, and means passing through the pole pieces and between the parts of the divided windings for retaining said side supports in position, substantially as described.

7. In a dynamo electric machine, the combination with the revolving element and field magnets thereon, of side supports for the windings of said magnets, and means engaging the pole pieces and extending between parts of the winding for each pole piece for retaining the said supports in position.

8. In a dynamo electric machine, the combination with the revolving element and field magnets thereon, of side plates for the windings of said field magnets, and means engaging the pole pieces and passing through the windings for retaining said plates in position.

9. In a dynamo electric machine, the combination with the revolving element and pole pieces thereon, of a divided winding for each of said pole pieces, side supports for the windings, and means engaging the pole pieces and passing between the parts of the divided windings for retaining said side supports in position.

10. In a dynamo electric machine, the combination with the revolving element and pieces thereon, of a divided winding for each pole piece, side supports for the windings extending between the core and tips of the pole pieces, and means engaging the pole pieces extending between the divided winding of each pole piece for retaining said side supports in position.

In testimony whereof I affix my signature, in presence of two witnesses.

BERNARD ARTHUR BEHREND.
